UNITED STATES PATENT OFFICE.

EDGAR E. SALISBURY AND ALBERT E. DEAN, OF TACOMA, WASHINGTON,
ASSIGNORS TO THEMSELVES AND FRANK B. TAYLOR, OF SAME PLACE.

CALL-BOX SYSTEM.

SPECIFICATION forming part of Letters Patent No. 605,345, dated June 7, 1898.

Application filed June 22, 1897. Serial No. 641,773. (No model.)

To all whom it may concern:

Be it known that we, EDGAR E. SALISBURY and ALBERT E. DEAN, of Tacoma, in the county of Pierce and State of Washington, 5 have invented a new and Improved Messenger-Call-Box System, of which the following is a full, clear, and exact description.

This invention relates particularly to call-box systems in which the telephone forms an 10 important part and also to the method of operating an electric or magnetic speaking-transmitter from a point to or from the central office over a permanently-magnetized circuit without the use of a local battery to operate the same and to a system of wiring the 15 central office which will also obviate the use of a local battery on the telephone; and the object is to cut the primary circuit of a coil within which the transmitter is located in and 20 out of the main-line circuit when either in use or not in use, as the case may be, without disturbing the secondary, which is the local circuit, in this case independent from the main line, and within which is located the hand-telephone— 25 that is, the portion of the induction-coil which has the least resistance and wound inside or sufficiently near to be capable of transmitting an induced current to the secondary part of the coil is cut in and out of the 30 main circuit when in use or not in use, as will hereinafter appear.

Another object is to provide a simple means of signaling the central office when hanging up the receiver, to indicate that the subscriber 35 is through with the conversation, and also to enable the subscriber to carry on conversation with the central office by operating push-buttons to close a circuit through a ground-line when the main wires are short-circuited or 40 broken.

We will describe the telephone system embodying our invention, and then point out the novel features in the appended claims.

Reference is to be had to the accompanying 45 drawings, forming a part of this specification, in which similar characters of reference indicate corresponding parts in all the figures.

Figure 1 is a diagrammatic view of the telephone part of the central-office wiring system. 50 Fig. 2 is a detail showing the circuit-closing plug as connected with contact-points, and

Fig. 3 is a diagrammatic view showing the wiring in the call-box.

Referring to the drawings, 1 designates the incoming main wire, and 2 indicates the outgoing main wire, and with these two wires connections are made from a telephone or telephones 3 in the usual manner. This telephone 3 indicates a substation apparatus.

The spring-contact 11 is normally in engagement with a similar spring-contact 18, extending from a binding-post 19, and from this binding-post 19 a wire 20 extends to a connection with the outgoing main-line wire 2. The circuit enters from the main wire 1 60 through the wire 23, which connects with the binding-post 10, to which is attached a spring 11. It will thus be seen that a metallic circuit may be secured from any one of the outlying instruments 3 over the main-line wires 65 1 and 2 to the central office through the springs 11 and 18.

From the transmitter 24 a wire 25 extends to a connection with a spring contact-finger 34, adapted to be put in connection with the 75 contact-finger 18 by reason of inserting the plug 29, the body portion of which is of insulating material. From the other binding-post of the transmitter 24 is extended a wire 36 through the primary circuit of the coil over 80 the wire 37 to contact-finger 35, adapted to be put in connection with the contact-finger 11.

The hand-telephone is locally and permanently connected (in a local circuit containing no battery) through the secondary circuit 85 of the coil by wires 38 and 39 and independently from the main-line wires.

A main battery, relay, and other apparatus ordinarily used on a call-box circuit to register the number of an outlying instrument are 90 connected in the main-line circuit at the central office in the usual manner.

The springs 26 and 27 are designed to engage with the metal point 28 of the plug 29 for the purpose of short-circuiting the call-box apparatus while using the telephone. 95

When the plug 29 is inserted in the telephone-switch, the springs 11 and 18 are parted at the point and connected, respectively, with the spring-contacts 35 and 34, thus extending 100 the metallic circuit through the transmitter and primary portion of the coil.

We will now describe our improvements and additions to the call-box mechanism.

An ordinary call - box movement, which needs no description, having a frame 51, is arranged within the transmitter-box 3. To the winding-arbor 50 is attached a support-lever 48, having a bifurcated outer end with which is to be engaged the receiver 49 in the usual manner. This lever 48 has a pin-hinge 52, 10 designed to open one way only and to prevent any unnatural progress of the call-box movement by reason of an upward pressure at the outer end of the lever 48. The lower end of this lever 48 within the box has a lug 53, 15 designed to engage with a pin 54 (which is securely attached to the insulating-block 56) in such a manner as to lift the ends of the contact-fingers 70 and 71 away from the break-wheel 56 when the support-lever 48 is moved 20 to its extreme downward position.

Securely fixed to the frame 51 is a spring 55 with a slight pressure against the movable insulating - block 56, designed to hold it in such a position that the contact-springs 25 70 and 71 will engage with the teeth on the break-wheel 56 when the same is in motion.

Stationarily fixed to the frame 51 is an insulating-block 68, to which is attached a contact-finger 69^a, adapted for engagement with 30 the circuit-closer 61, which extends outward from the inner end of the lever 48.

The circuit-closing fingers 70 and 71 are normally open and are adapted to be closed intermittently by the break-wheels. From the finger 70 a wire 72 extends to a binding-post 73, and from this binding-post 73 a grounding-wire 74 is extended. The wire 72 also leads to ground contact-pieces 79 and 75. From the contact-finger 71 a wire 77 extends to a contact-piece 78, designed to disengage with the contact-piece 76 and engage with the contact-piece 75 when the button B is pressed down. From the contact-piece 76 a wire 82 leads to a connection with the incoming main wire 1. 35 A shunt-wire 83, leading from the wire 82, is connected with a spring-finger 84, designed to be engaged by a circuit-closing finger 85, arranged near said finger 84. From the frame 51 a wire 79 extends to a contact-piece 81, 40 designed to disengage with the contact-piece 85 and engage with the contact-piece 69 when the button B' is pressed down. From the contact-piece 85 a wire 80 leads to a connection with the outgoing main wire 2. The receiver 49 is connected in an independent local circuit by itself through the secondary part of the coil by wires 86 and 87. From the contact-finger 69 a wire 91 extends through the primary part of the coil to one of the 45 binding-posts of the transmitter, and from the other post of the transmitter a wire 93 leads to a connection with the contact-finger 71.

In operation when the receiver is removed and the lever 48 is at its extreme upward position, as shown in Fig. 3, the metal circuit-closer 61 engages the contact-finger 69^a. In this position the primary circuit is cut in—

that is, the main circuit is then closed through it. This will be seen by following the circuit from the line 1 over the wire 82, contact-piece 76, spring 78, wires 77 and 93 through the transmitter and primary over the wire 91, contact-finger 69^a, circuit-closer 61, and thence through the movement over the wire 79, spring 81, contact-piece 85, and over the wire 80 to outgoing line 2. When the lever 48 is at its extreme downward position, the primary circuit is cut out by reason of the fact that the circuit-closer 61 is then disconnected from the contact-finger 69^a and stands in position 80 to clear that and all other contact-fingers. Then the wire 91 ends at the contact-closer 69^a, and the circuit within which the primary coil and transmitter are located is dead from the contact-finger 69^a to a point where the 85 wire 93 joins the wire 77.

The push-buttons B and B' when pressed down are used to establish the ground-circuit for carrying on conversation with the central office when the wires 1 and 2 are crossed or short - circuited or when either is broken. The operation of the buttons opens either the outgoing or incoming wires at the contact-pieces 76 or 78 and at the same time establishes a ground on the opposite side of the 90 telephone from either wires 1 or 2. For instance, when the button B is pressed down the spring 78 engages the contact-piece 75, and the contact-piece 75 is grounded by means of the wires 72 and 74. From this ground a 100 circuit is established for conversation over the wires 77 and 93 to the transmitter, thence through the primary coil, wire 91, contact-finger 69^a, and circuit-closer 61 to and through the movement, thence over the wire 79, spring 105 81, contact-piece 85, and thence over the wire 80 to line-wire 2 to the central office, which is provided with a ground on the opposite side of its telephone through the ordinary district apparatus. It will also be seen that 110 when the button B is pressed downward the wires 1 and 82 are dead or cut out, because the line ends at the contact-piece 76. Hence in the case of a cross between the wires 1 and 2 the telephone at the call-box is not cut out. 115 The same result is obtained when the button B' is pressed down, except that conversation is carried on from the ground established at the box to the one at the central office over the wire 1 instead of the wire 2, and wires 2 120 and 80 are dead or cut out.

In explaining the coöperation of the arm 61 with the contacts 85 and 84 it may be stated that said contacts are only put into engagement upon the downward movement 125 of the lever 48. It will be noted in the drawings that the contact 85 is somewhat longer than the contact 84, and this lengthened end is in the arc of the circle described by the arm 61. Therefore when the receiver is lifted 130 from the lever 48 the arm 61 will engage with the contact 85 and move it away from the contact 84. When the receiver, however, is placed upon the lever 48 and the lever is

5 moved downward, the arm 61 will engage with the extended end of the contact 85 and press it into engagement with the contact 84, thus momentarily closing the circuit to indicate to the office that the call is finished. It will be noted that the circuit-closing arm 61 will not be in engagement with either one of the contact-fingers 84 or 85 when the instrument is not in use.

10 The central-office receiving and registering device and the several connections and operation may now be described.

The receiving device in our system consists of two relays, one being regular and the other extra, the local points of which are connected to operate both sides of a double-pen register in the ordinary manner. The regular relay 12^a is arranged to operate one pen of the register, while the extra relay 12^b operates the 15 other pen. Both relays stand open with armatures drawn away from the magnets when the line is in normal condition and not in use. As here shown, the local register-circuits are open at the contact-points of the relay-armatures. The regular relay responds to any intermittent or permanent closing of the wires 20 1 and 2 at any point on the circuit. Hence if the receiver 49 at a call-box is removed and the lever 48 is released then a movement of 25 the call-box will cause the wheel 56 to make one-half of a revolution, causing the brushes 30 70 and 71 to contact with the wheel 56 as many times as there are segments or projections on the wheel, which are three in this 35 case. These contacts operate to close the circuit three times, which closing causes the regular and extra relays to be energized the same number of times, and each action of the relays by reason of these closings operates the 40 local circuits to record the number "3" on the register-tape.

The metallic circuit formed by reason of the brush 71 contacting with the brake-wheel 56 is traced as follows: Beginning at the positive pole of the battery A at the central office, over the wire 12 to the regular relay 12^a, thence over the wires 13 and 14 to binding-post 19, through contact-fingers 18 and 11 to binding-post 10, thence over wire 23, 45 binding-post 4, and outgoing-line wire to a point at the box where wire 1 intersects with wires 82 and 83. Thence the circuit continues over wire 82, contact-piece 76, spring 78, wire 77, brush 71, thence to the brake-wheel 56, thence over wire 79, spring 81, contact-piece 55 85, wire 80 to wire 2, thence over return-wire 2 to binding-post 3 of the five-point switch at the central office, thence over the left-hand lever of the switch, binding-post 5, wires 20 and 15 to the negative pole of the battery A, thus completing the metallic circuit from any 60 one of the outlying boxes.

The extra relay 12^b responds to any intermittent or permanent ground thrown on either 65 or both of the line-wires 1 2 at any point upon the circuit. Hence when the brush 70 in the call-box contacts with the segments or

projections on the brake-wheel 56 in the same manner as the brush 71, heretofore explained, closings will be made to cause the extra relay 70 to be energized the same number of times as there are segments or projections on the side of the break-wheel. This will operate another local circuit to record the number of the box on the opposite edge of the register-tape from that of the regular relay. This circuit is traced as follows: from the ground at the central office over wire 16 to binding-post 6 of the five-point switch, over the right-hand lever of said switch to binding-post 7, 80 thence by wire 17 to the negative pole of the battery A', and from the opposite pole of this battery by wire 21 to the extra relay, and then by wires 22 and 15 to the negative pole of the battery A, and from the opposite pole 85 of this battery by wire 12 to the regular relay, thence by wires 13 and 14, binding-post 19, contacts 18 and 11, binding-post 10, wire 23, binding-post 4, over main-line wire 1 to a point where wire 1 intersects with wires 82 90 83 at the call-box, thence by wire 82, contact-piece 76, spring 78, wire 77, brush 71, thence across through the segment of the brake-wheel 56 to brush 70, thence by wire 72, binding-post 73, and wire 74 to the ground, thus 95 completing a metallic circuit from the central office to the call-box over line-wire 1 by using the earth as a return-path current and causing the extra relay to respond simultaneously with the regular relay. The extra-relay circuit also has another path over the incoming wire 2, which is traced as follows: from the ground at the central office over wire 16 to binding-post 6, thence over the right-hand lever of the five-point switch to 100 binding-post 7, wire 17 to the negative pole of the battery A', and from the opposite pole of this battery over wire 21 to the extra relay, thence by wires 22 and 20 to binding-post 5, through left-hand lever of switch to 110 binding-post 3, thence over the main-line wire 2 to wire 80 at the call-box, then over wire 80, contact-piece 85, spring 81, wire 79, wheel 56, spring 70, thence by wire 72, binding-post 73, and wire 74 to the ground, thus 115 completing a circuit from the central office to the call-box over line-wire 2 by using the earth as the return-path.

It will be seen that when a box is turned in and no wire trouble exists both the regular 120 and extra relays operate simultaneously and record the same number on both edges of the register-tape. Should either of the line-wires 1 or 2 become broken, the call would then come in over the intact-wire on ground-surface and be recorded on the extra relay. A short circuit between wires 1 and 2 or contiguous wires at any point will be instantaneously detected, as the regular relay will permanently close, and a prolonged signal will be received 125 on the side of the register operated by the same. The dotted lines show the five-point switch at the central office as thrown to the left, joining wires 1 and 2 together at binding-

post 4 and grounding the negative end of the regular battery through the right-hand lever of the five-point switch. Calls will then be received from the outlying boxes over both 5 wires 1 and 2, the binding-post 4, thence over wire 23, binding-post 10, springs 11 and 18, binding-post 19, wires 14 and 13 to the regular relay 12^a, thence over wire 12 to the positive pole of the battery A, and from the negative 10 pole of this battery to the ground over wires 15 and 20, binding-post 6, and wire 16.

Our method of using the telephone in the box during wire trouble and rendering the 15 same serviceable through the manner of effecting a ground has been heretofore explained. The parts 26 and 27 are used to cut out the relay when talking. While the plug 29 remains inserted in the switch to cut in the telephone, as shown in Fig. 2, the metal point 28 20 contacts with the spring-fingers 26 and 27 and serves to shunt the relay by forming a short circuit from one of the binding-posts of the regular relay over wire 30, binding-post 8, spring 27, metal point 28, spring 26, wires 31 25 and 13 to the other end of the regular relay.

It will be noted that this device works on an open circuit and that neither of the ground or line contact-fingers comes in contact with the break-wheel excepting when in motion.

30 It will also be noted that no local batteries are used either at the instrument or central office in the operation of the telephone.

Having thus described our invention, we 35 claim as new and desire to secure by Letters Patent—

1. The combination of a signaling mechanism, comprising a call-box movement, a receiver, a supporting-lever mounted on the main arbor of said movement, a circuit-closer 40 extended from the inner end of the lever, a contact-finger in the main line for engagement therewith, a circuit-closing switch for the main line comprising contact-fingers and adapted to be operated by the circuit-closer 45 carried by the lever upon the downward movement of said lever, and connections comprising a grounding-switch between the main line and said circuit-closer carried by the lever, substantially as specified.

50 2. In a call-box system, the combination of a swinging hinge-lever for supporting a receiver, a call-box movement for moving said lever in one direction, a circuit-closer operated by said lever, circuit-closing fingers for

55 the main line, means operated by a downward movement of the lever to operate said fingers and momentarily close the main line, and means comprising two switches for grounding

and opening the circuit should the main line become inoperative, substantially as specified.

3. In a call-box system, a call-box mechanism comprising a lever containing a hinge and adapted to support a telephone-receiver, a movable insulating-block, and supporting circuit-closers arranged in a shunt-circuit from the main line and adapted to a change of position by engagement with the support-lever when said lever is at its extreme downward movement, substantially as specified.

4. A call-box mechanism, comprising a hinged receiver-supporting lever, a circuit-closing finger carried by the said lever and having connection with the main line, a fixed finger with which such movable circuit-closing finger is designed to engage, a wire extended from the fixed finger to a transmitter, the said wire comprising a resistance, a wire extended from the transmitter to another fixed contact-finger 71 arranged for connection with the main line, means for closing a central-office-signaling-device circuit upon a downward movement of the hinged lever, and a local circuit comprising a resistance and receiver, said resistance being wound in close proximity to the resistance contained in the wire leading to said transmitter, substantially as specified.

5. A messenger-call system, comprising main wires, a battery in the main wires for 90 operating all the call-boxes, an ordinary call-box circuit, normally-closed contact-fingers arranged in said circuit, an auxiliary circuit 25, 36, 37, comprising a resistance and transmitter, and means for connecting said auxiliary circuit with the main-line wires, substantially as specified.

6. A messenger-call system, comprising main wires, a battery in the main wires for 100 operating all the call-boxes an ordinary call-box circuit containing the usual apparatus for operating the same, normally-closed contact-fingers arranged in said circuit, an auxiliary circuit 25, 36, 37, comprising a resistance and transmitter, means for connecting 105 said auxiliary circuit with the main-line wires, and a local circuit comprising a resistance and receiver, said resistance being wound in close proximity to the resistance of the auxiliary circuit, substantially as specified.
